JUICE DISPENSER OR SIMILAR ARTICLE

Donald E. Holcomb, Brooklyn Center, Minn., assignor to
The Cornelius Company, Golden Valley, Minn.

Filed Dec. 29, 1972, Ser. No. 319,866

Term of patent 14 years

Int. Cl. D15—08

U.S. Cl. D94—3 A

Fig. 1

Fig. 2

FIG. 3

FIG. 4

FIG. 5

FIG. 1 is a perspective view of a juice dispenser or similar article, showing my new design;

FIG. 2 is a front elevational view thereof;

FIG. 3 is a rear elevational view thereof;

FIG. 4 is a side elevational view thereof, the opposite side being a reverse image thereof; and

FIG. 5 is a top plan view thereof.

The bottom, not shown, is plain and unornamented. I claim:

The ornamental design for a juice dispenser or similar article, substantially as shown and described.
